CLAIM

The ornamental design for a blown glass pendant for decorative light fixtures, as shown and described.

DESCRIPTION

FIG. 1 is a front elevational view of a blown glass pendant for decorative light fixtures showing any new design;

FIG. 2 is a left-side elevational view thereof;

FIG. 3 is a right-side elevational view thereof;

FIG. 4 is a rear elevational view thereof;

FIG. 5 is a top plan view thereof;

FIG. 6 is a bottom plan view thereof;

FIG. 7 is a top perspective view thereof; and,

FIG. 8 is a front perspective thereof.

The broken lines shown in the drawings are directed towards environment and unclaimed portions of the pendant, and form no part of the claimed design.

1 Claim, 4 Drawing Sheets
